Munn, Ladd & Gelbaum
ATTORNEYS

My invention relates to a device for massaging and cleaning, and especially to a device for use in treating teeth and gums. It is well known that many people require their teeth and gums to be massaged and cleaned, but it is sometimes difficult to find ordinary brushes with bristles of just the right stiffness, since some people can use a brush with very stiff bristles and others whose teeth and gums are more tender require a softer brush. Furthermore, the bristles being closely spaced on an ordinary brush do not very readily enter very deeply into the spaces between the teeth where often food lodges. Because of this difficulty many people are required to use dental floss in addition to the ordinary toothbrush in order to effectively remove all food particles from between their teeth.

This invention relates to a new and useful improvement in a device for massaging and cleaning and is especially adapted for use in so treating teeth and gums.

It is well known that many people require their teeth and gums to be massaged and cleaned, but it is sometimes difficult to find ordinary brushes with bristles of just the right stiffness, since some people can use a brush with very stiff bristles and others whose teeth and gums are more tender require a softer brush. Furthermore, the bristles being closely spaced on an ordinary brush do not very readily enter very deeply into the spaces between the teeth where often food lodges. Because of this difficulty many people are required to use dental floss in addition to the ordinary toothbrush in order to effectively remove all food particles from between their teeth.

In massaging teeth and especially the gums thereof an important consideration is to have a device which is firm in one sense and yet flexible enough on those portions coming in contact with the gum so as not to bruise or irritate them. In the use of ordinary tooth brushes for this purpose, there is no variation in the stiffness of the bristles from the bottom to the top thereof.

This invention aims to provide a device which will overcome these disadvantages and avoid the deficiencies above mentioned and enables one to massage the gums effectively while at the same time not subjecting them to stiff rubbing action and in the same device providing rubbing elements for the teeth which are so formed as to enable them effectively to get down in between the teeth and remove particles of food.

A still further object is to provide a simple, economical device which can be used to gently massage the teeth and the gums and other portions of the mouth by a combination of pressure and suction.

Still another object is to provide a simple article which will more efficiently retain on itself the medicine, cleansing material and the like at its point of contact with the gums and the teeth so that smaller quantities of such material need be used.

Further and more specific objects, features and advantages will more clearly appear from a consideration of the detailed specification hereinafter set forth, especially when taken in connection with the accompanying drawings which illustrate a present preferred form which the invention may assume and which form part of the specification.

MASSAGING AND CLEANING DEVICE

John T. Haeusser, Albany, N. Y.

Application January 13, 1948, Serial No. 1,982

1 Claim. (Cl. 128—62)

1

2

In brief and general terms the invention comprises a brush having a body portion, the top surface of which has formed therein a series of concave recesses with common intervening walls, the tops of which are relatively thin and flexible to project into the spaces between the teeth for cleansing purposes and the concavity of which recesses will act as retainers for the cleansing material. The recesses also act as suction cups when pressure is applied to the device so as to enhance the massaging action of the device on the teeth and the gums and adjoining parts of the mouth. The top sectional shape of the cavities is somewhat rectangular with curved corners, a shape which will permit easy and certain action on the portions of the teeth where they join the gums. The common walls between the recesses are relatively broad at the bottom but taper to a relatively thin edge at the top so as to be flexible for massaging purposes and certainly project into the narrow depressions between the teeth for proper cleaning results. The breadth at the bottom of the common walls and the thinness at the top are achieved by forming the wall faces with intersecting concave curves.

Preferably, these cavities are formed on a common base which can be connected to the body of the brush which may have a proper handle. In a preferred form the cavities and the supporting base on which they may be formed are molded of some suitable material such as rubber or the like, and this unit may be attached to the body of the brush in any suitable manner adapting it to be removed when sufficiently worn and replaced by a new unit.

A present preferred embodiment of the invention is shown in the drawings in which—

Fig. 1 is a side view of the device with the upper portion broken away;

Fig. 2 is a vertical cross section taken on the line 2—2 of Fig. 1;

Fig. 3 is a plan view of the device;

Fig. 4 is a vertical longitudinal section through a modified form of the device; and

Fig. 5 is a vertical cross section taken on the line 5—5 of Fig. 4.

Referring now merely to the specific forms of the invention illustrated in the drawings, it will be seen that the novel unit comprising my invention includes a base portion 10 preferably of rubber or similar material adapted to be seated in a recess 11 formed in the body 12 of a brush provided with a suitable handle 13. Instead of the base 10 being seated in a recess, it may be formed

as shown in Fig. 4 with a central bore 14 into which the body portion 15 of the brush may be inserted. In this case the handle 13 will be provided with a shoulder 16 to limit the insertion of the body 15 and properly relate the elements.

A base 10 made of rubber or similar material is preferably molded and has formed on its upper surface a series of closely spaced concave cavities generally nominated by the numeral 17. These cavities are preferably molded integral with the base 10, but it is within the purview of this invention that they may be formed separately and attached to the support or base in any suitable manner. Each cavity preferably is in horizontal section rectangular with curved corners 18. Common walls 19 between the cavities 17 are formed preferably by two concave curves. The walls are broad relatively at the bottom and taper to a relatively thin top edge as shown. This breadth at the bottom with a gradual taper gives the wall sufficient fundamental strength and firmness to permit vigorous massaging and scrubbing action without rapid deterioration. Near the top of each wall its curvature is interrupted by another intercepting concave curve which more rapidly reduces its thickness, whereby it terminates at the top in a narrow elongated edge 20. As seen in Fig. 3, it will be noted that the cavities extend practically the full width of the base 10 transversely of the length of the base thus giving plenty of support and a narrow upper edge the full width of the device which gives ample surface for the massaging of teeth and gums. The provision of the double concave curvature to the walls gives a narrow relatively thinner upper portion which results in this portion being somewhat more flexible and sufficiently so to effect the scrubbing and massaging of the teeth without being so stiff as not to give somewhat and avoid irritating and injuring the gums. The narrowness of the upper edges also permits them to enter the spaces or indentations between the teeth to effectively remove food particles. Pressure on the device will force it against the teeth and permit the cavities to act as pumps and suction devices to force contained cleansing material into and between the gums and teeth and to massage the gums more effectively.

It will thus be seen that I have provided a simple, strong, compact, durable device which can massage the teeth and gums effectively with

a combined pressure and suction action; will afford a recess to receive the cleansing material and get it to the surfaces to be treated without so much loss and in action will force it more effectively on to the said surface. The common intervening walls with their thin upper edges will afford an efficient flexible means to enter the depressions between the teeth to effectively remove any solid matter which may have lodged therein and also to more thoroughly clean these portions. The device is simple and economical to manufacture, since it can be molded in one piece by very simple molding operations and then adapted to either form of handle shown. The soft smooth surfaces without sharp pointed bristles permit vigorous action on the teeth and gums to give them plenty of exercise and increase the circulation in the gums without creating any soreness or irritation therein.

While the invention has been described in detail and shown with respect to the accompanying drawing, it is not to be limited to such details, since many changes and modifications may be made in the invention without departing from the spirit and scope thereof. Hence, it is desired to cover any and all forms and modifications of the invention which may come within the language and scope of the appended claim.

What I claim as my invention is:

A cleaning and massaging brush for the teeth and gums comprising a longitudinally extending body portion of resilient material, said body portion having upstanding walls at each side thereof, and a plurality of spaced transversely extending walls connecting the side walls and cooperating therewith to define a plurality of segregated cavities adapted to contain a dentifrice, said transverse walls and said side walls being adapted to clean and massage the teeth and gums.
